UNITED STATES PATENT OFFICE.

GEORGE K. HENDERSON, OF INDIANAPOLIS, INDIANA, ASSIGNOR TO INTERNATIONAL PRINTING COMPANY, OF INDIANAPOLIS, INDIANA, A CORPORATION.

MULTICOLOR-PRINTING PRESS.

1,254,500.

Specification of Letters Patent. Patented Jan. 22, 1918.

Application filed April 3, 1916. Serial No. 38,547.

To all whom it may concern:

Be it known that I, GEORGE K. HENDERSON, a citizen of the United States, and a resident of Indianapolis, county of Marion, and State 5 of Indiana, have invented a certain new and useful Multicolor-Printing Press; and I do hereby declare that the following is a full, clear, and exact description thereof, reference being had to the accompanying drawings, in which like letters refer to like parts.

The object of this invention is the printing of two or more colors by one machine and in one operation, the blank stock being fed in at one end of the machine and issuing 15 from the other end of the machine as a completed product with a plurality of colors thereon:

The chief feature of the invention consists in forming the press or machine of a 20 plurality of units, there being one unit for each color that is to be applied to the stock. Each unit is self contained and includes its own impression cylinder, a plate carrying cylinder, an inking train and an ink fountain, all independently adjustable as to pressure and position and ink flow. These units are arranged in the press or machine in 25 succession so that the sheet of paper stock passes through the series of units, and as it passes each unit, a certain color is applied by such unit. Said sheet of paper passes between the impression cylinders and the plate carrying cylinders of the units and is fed by them so that the parts of adjacent 30 units coöperate in the work. While one unit is applying a certain color, the other units are coöoperating therewith by feeding the sheet of paper and in succession applying other colors.

40 The series of units are mounted on one base in a definite relation with each other and they are driven by a single means and, therefore, the operation of all units is controlled from a single source and simultaneously actuated. There is no backlash or 45 loose gear motion, and perfect registration of the units is thereby guaranteed.

The advantages of such a machine are 50 very great, particularly on account of speed and saving of cost. Thus a single machine, either sheet or roll feed, will turn out from three thousand to six thousand or more sheets per hour and applies thereto any de-

sired number of colors with accuracy. Such machine can be used for lithographical as 55 well as typographical purposes.

Another feature of the invention consists in the means for simultaneously elevating the plate carrying cylinders so that they will not print. This is of service while inking 60 or working on one of the units and it does not interfere with the operation of the machine otherwise as the cylinders can continue to rotate, but will not contact with the sheet of paper to be printed or colored. Also the 65 arrangement is such that any one of the plate carrying cylinders instead of all may be elevated out of printing contact with the sheet of paper.

Another feature of the invention consists 70 in means, in a multiple color printing machine, for so operating the device as to color both sides of the sheet of paper. The sheet may be colored on the back side from one of the cylinders or units and the other cylinders 75 or units apply multiple colors to the other side.

The full nature of the invention will be understood from the accompanying drawings and the following description and 80 claims:

In the drawings, Figure 1 is a side elevation of the machine. Fig. 2 is a vertical transverse section through a portion of the machine, parts being omitted and parts being 85 indicated by dotted lines. Fig. 3 is a section through a portion of the machine on the line 3—3 of Fig. 2, most of the portion of the machine, however, shown in section being in side elevation, and the parts being 90 shown in their position when the plate carrying rollers are elevated away from the sheet of paper and impressing rollers. Fig. 4 is a vertical section through a portion of the machine on the line 4—4 of Fig. 2, the 95 parts of the machine being shown in their position while color printing. Fig. 5 is a figure like that shown in Fig. 3, but a modified form arranged so as to color both sides of the sheet of paper. Fig. 6 is a reproduction of a portion of the lower left-hand corner of Fig. 5, showing the parts in altered position.

The machine shown in Fig. 1 has a horizontally disposed frame adapted to rest on 105 the floor and provided with four units, A,

B, C and D, for printing four colors. Each unit supplies to the sheet of paper 10, as it passes through the machine, a different color from that of each of the other units. In the 5 operation of said machine, the sheet 10 moves continuously through the machine and receives the colors. The machine and invention are not limited to any particular number of units and in fact all of the units 10 need not be simultaneously used; but the idea of the invention is the use of a plurality of units for printing a plurality of colors on a sheet of paper. The sheet of paper is unwound from a roller 11 mounted 15 in a roller carrying mechanism 12 and located at one end of the machine, and the printed sheet of paper is received from the other end of the machine by the usual cutting and distributing mechanism 13, only a 20 portion of which is shown, as it may be of any desired arrangement so far as this invention is concerned.

The frame 15 may be made in any desired way, either as a solid frame, but preferably 25 in sections, as shown, said sections being secured together at their unions and being secured to a continuous base 16 so as to make the frame unitary and rigid.

Each color unit, A, B, C or D, includes an 30 impression cylinder 20 carried by a shaft 21 mounted in a rigid bearing 22 in the main frame 15, as shown in Figs. 2 and 4. The bearing 22 rests on a plate 23 on the frame so that said roller cannot be forced downward. 35 Above said impression cylinder there is a plate carrying cylinder 24 on a shaft 25 mounted in a bearing 26 vertically movable in the main frame 15. A side elevation of this bearing construction is shown in Figs. 40 3 and 5, suitable vertical guides 126 being secured to the frame for guiding the vertical movement of the bearings. There is opportunity in said frame for a slight vertical movement of the bearings of said cylinder 45 shafts, for the purpose hereafter explained, but the movement permitted is not sufficient to disengage the gear 30 on the shaft 21 from the gear 31 on the shaft 25, whereby the plate carrying cylinder 24 is driven.

50 The gear 30 is driven by a beveled gear 32 on the shaft 21 which engages a beveled pinion 33 on a driving shaft 34 that extends for most of the length of the machine and is mounted to the main frame by bearings 35. 55 Said shaft 34 is driven by gears 37 and 38 transmitting power from a transverse shaft 39 which carries a driven pulley 40 located on the other side of the machine.

This driving mechanism starts and operates all of the units, A, B, C and D, simultaneously and there is no back lash or lost gear motion and perfect registration of the units is guaranteed.

Each unit in addition to the impression 65 cylinder and the plate carrying cylinder has

means for supplying ink in proper condition to the plate carrying cylinder. The details of this mechanism are not material to the particular invention sought to be covered herein, and, therefore, the same need not be 70 fully described. There is, however, as shown in Figs. 1 and 4, an ink fountain 41 mounted above the plate carrying cylinder, damping rolls 44 and an inking train including a series of inking rolls 42, and vibratory 75 inking rolls 43. These rolls are all mounted in U-shaped bearings 45 extending upwardly so that the roller spindles seat themselves in the bearings by gravity and are thus vertically movable and do not interfere with the 80 vertical movement of the plate carrying cylinder and all parts are independently adjustable as to pressure, position and ink flow. These bearings are all connected with frame extensions 46 on each side of the machine 85 and extend up from the main frame.

A plate carrying cylinder of each unit is capable of being elevated out of printing engagement with the sheet of paper by the following means: A lever 50 is fulcrumed 90 to the frame 15 at 51 and between its ends it is connected by a link 52, with a downwardly extending ear 53 from the vertically movable bearing 26 of the shaft 25 of the plate carrying cylinder 24. The free end of 95 the lever 50 is yoke-shaped and fits astride a cam 55 on a short cam shaft 56 mounted in the main frame and turned by a hand lever 57. When the lever 59 is in its vertical position, as shown in Fig. 5, the plate carrying cylinder 24 will be in its down-most position and in operative printing engagement with the sheet of paper or in pressure engagement with the impression cylinders below, as indicated in Fig. 4. When, however, the lever 57 is moved to the horizontal position, shown in Fig. 3, the plate carrying cylinder will be elevated, as shown in Fig. 3, out of contact with the sheet of paper. This is a feature of considerable value in the 100 multiple color printing machine as the printing units' operation can be stopped for re-inking or any other purpose without stopping the operation of the machine as a whole. Furthermore, it may be desired that only 115 three colors shall be run for a certain job, and one of the units must be put out of operation. This is done by moving the lever 57 to the position shown in Fig. 3 and latching it down.

120 Since there is a plurality of units, it is desirable ordinarily that all of the plate carrying cylinders shall be simultaneously elevated out of operation or lowered into printing position. This is accomplished by 125 a number of crank arms 60 extending rigidly from the cam shafts 56 and being pivotally connected with each other by a connecting rod 61. It is evident, therefore, that when one plate carrying cylinder is elevated, all 130

of them will be simultaneously elevated. The connection, however, between the elevating means for the different units should be readily disengageable, as for instance, by 5 removing a cotter pin 62 so as to disconnect the crank rod 60 from the connecting rod 61. This is important when it is desired to print 10 only three colors and, therefore, stop the operation of an entire unit while such job 10 is passing through the machine. In that event, one unit will be elevated and out of printing condition, but the plate carrying cylinders of all the other units will be simultaneously elevated and lowered by the operation 15 of any hand lever 57.

A modified form is shown in Figs. 5 and 6, for it is often desired to color both sides of a sheet of paper where there are a plurality of units. Fig. 5 illustrates the machine 20 with the left-hand end modified, the right-hand units being broken away, and arranged so that the left-hand unit will color the under or back side of the sheet of paper, while the other units will apply their 25 colors to the upper or main side of the paper.

To accomplish the foregoing, the sheet of paper 10 runs from the roller 11 over rollers 70 on a frame 71 secured on the upper end 30 of the frames 46 of two of the units and passes down vertically between the first two units past an eccentric roller 65 adapted to be adjusted to cause the paper to travel over a greater distance between said units and 35 under a roller 72 and over an oscillatory compression cylinder 73 under and in pressure engagement with the impression cylinder 20 of the first unit, as shown in Fig. 5. Ink is applied to the reverse side of a sheet 40 of paper by the impression cylinder 20 and then the sheet of paper passes from cylinder 73 to the remaining units in the machine, whereby the remaining colors are applied to the upper surface of the sheet of paper. 45 The cylinder 73 is held upwardly into operative position with the main impression cylinder 20 by supports 74, the upper ends of which carry the spindles of the cylinder and are held in place and guided between 50 two oppositely located guides 75. The lower end of the support 74 is pivoted at 76 to a rocking frame 77 which turns on a center at 78 when a lever 79 is moved. Thus when the lever 79 is in its lower position, as shown in 55 Fig. 5, the toggle joint support for the cylinder 73 will force it upward into printing position. When the lever 79 is elevated to the position shown in Fig. 6, it will lower the cylinder 73 away from the impression 60 cylinder 20 and be out of printing position.

When the machine is equipped with the modified structure, as shown in Figs. 5 and 6, and it is desired to apply all of the colors to only one side of the sheet, as in Fig. 3, the 65 lever 79 and the means for positioning the

cylinder 73 are maintained in their inoperative position, as shown in Fig. 6. When it is desired to color both sides of the sheet of paper, the sheet is carried around the cylinder 73 and then it is forced upward into 70 printing position.

The machine herein described, while relatively simple in plan and construction, has remarkable utility and capacity. It will apply one or more colors, as desired, to one 75 side, and one color to either or both sides of the sheet of paper, as fast as the sheet of paper can be fed. And it may be stated that the invention is not limited to a roll feed, as separate sheets of paper may be 80 fed through it also and then its speed will be as great as the ability of the feeding mechanism to position the sheets. Four thousand finished sheets per hour, in one, two, three and four colors is the normal 85 running speed, and the speed may vary from three to six thousand sheets per hour according to the class of work being run.

The chief value of the machine, however, arises from the multiple color work. It can 90 complete work in two colors at twice the output of the flat bed presses, as no intermediate cylinder is required and the registration of the second color can be absolutely guaranteed. It can complete work in three 95 colors at one operation at twice the productive rate of the two-color flat bed and single color flat bed presses combined. It can do work requiring four colors at one operation at twice the productive rate of two 100 two-color flat bed presses combined.

This machine also is so arranged and operated, that it can use thin plates of zinc which is much more difficult than the regular curved electros and, therefore, is capable 105 of lithographic as well as typographic uses. It can be used for printing from planographic transfers, or curved etchings or electrotypes by modifying the plate carrying cylinders to suit the plates to be 110 used, as is well known to those familiar with the art.

The invention claimed is:

1. A multiple color printing machine including a main frame, a plurality of color printing units mounted therein in successive order, each unit including an impression cylinder and a plate carrying cylinder, the cylinders in the successive units arranged to simultaneously act on a sheet of paper passing through the machine, means for operating all of said cylinders simultaneously, each plate carrying cylinder mounted in vertically movable bearings and in position when actuated to elevate each of said bearings, a 115 cam construction for actuating the bearing for each unit, a crank arm connected with each cam, a connecting rod, and pins for removably pivoting said rod to each crank arm whereby power will be transmitted alike 120
2. A multiple color printing machine including a main frame, a plurality of color printing units mounted therein in successive order, each unit including an impression cylinder and a plate carrying cylinder, the cylinders in the successive units arranged to simultaneously act on a sheet of paper passing through the machine, means for operating all of said cylinders simultaneously, each plate carrying cylinder mounted in vertically movable bearings and in position when actuated to elevate each of said bearings, a 125 cam construction for actuating the bearing for each unit, a crank arm connected with each cam, a connecting rod, and pins for removably pivoting said rod to each crank arm whereby power will be transmitted alike 130

to all of said cams to afford the simultaneous vertical movement of all of the plate carrying cylinders.

2. A multiple color printing machine including a frame, a series of color printing units arranged in successive order in said frame, means for simultaneously operating all of said units, each unit having an impression cylinder and a plate carrying cylinder, 10 an auxiliary impression cylinder located in connection with the main impression cylinder for taking an impression from the main impression cylinder and reversing the paper for printing the opposite side thereof, and 15 means for moving said auxiliary cylinder into and out of engagement with said impression cylinders.

3. A multiple color printing machine including a frame, a series of color printing units arranged in successive order in said frame, means for simultaneously operating all of said units, each unit having an impression cylinder and a plate carrying cylinder, 20 an auxiliary cylinder located beneath the impression cylinder of one unit, means for 25 guiding a sheet of paper backwardly between said auxiliary cylinder and the ad-

jacent impression cylinder for printing the reverse side of the sheet of paper, and means for moving said auxiliary cylinder into and 30 out of engagement with said impression cylinder.

4. A multiple color printing machine including a frame, a series of color printing units arranged in successive order in said 35 frame, means for simultaneously operating all of said units, each unit having an impression cylinder and a plate carrying cylinder, an auxiliary cylinder located beneath the impression cylinder of one unit, means for 40 guiding a sheet of paper backwardly between said auxiliary cylinder and the adjacent impression cylinder for printing the reverse side of the sheet of paper, a pair of bars for supporting said auxiliary cylinder, 45 a rocking bearing in which said bars are pivoted at their lower ends, and means for rocking said bearing so as to elevate or lower said auxiliary cylinder into and out of operative position. 50

In witness whereof, I have hereunto affixed my signature.

GEORGE K. HENDERSON.
